UNITED STATES PATENT OFFICE.

DAVID W. STEVENSON, OF BERKELEY, CALIFORNIA.

DISPENSING CARD-CASE.

1,378,294.

Specification of Letters Patent. Patented May 17, 1921.

Application filed October 13, 1919. Serial No. 330,478.

To all whom it may concern:

Be it known that I, DAVID W. STEVENSON, a citizen of the United States, residing in Berkeley, in the county of Alameda and 5 State of California, have invented a certain new and useful Improvement in Dispensing Card-Cases, of which the following is a specification.

My invention relates to dispensing card 10 cases wherein telescoping casings are provided with means for dispensing a single card at each operation.

The object of my invention is to provide an improved case for retaining calling or 15 business cards and the like.

A second object of my invention is to provide means for dispensing a single card as desired from a card retaining case.

I accomplish these and other objects here- 20 inafter set forth by means of the device disclosed in the drawings forming a part of the present specification, and wherein like characters of reference are used to designate similar parts throughout the said specification 25 and drawings, and in which—

Figure 1 is a perspective view of one type of my improved card case;

Fig. 2 is a longitudinal section of the case, the closed position being indicated in dotted 30 lines;

Fig. 3 is a longitudinal section of the case in extended relation for filling;

Fig. 4 is a cross sectional view taken on the line 4—4 of Fig. 2 in the direction indicated;

Fig. 5 is an enlarged view of the dispensing clip and foot; and

Fig. 6 is a side elevation showing one modification of design of case that may be used.

Referring to the drawings the device is 40 seen to comprise an outer casing 1, open at one end thereof to receive an inner casing 2 telescoping therewith and retaining a plurality of cards 3 therein. A spring metal clip 4 having a bearing foot 6, provided with a friction producing pad 7 suitably secured thereon, is secured on the inner surface of the top of the outer casing 1 by suitable rivets 5.

The inner casing 2 is provided at its outer 50 end with an inclined wall 9 and a slot 10 through which the cards 3 are singly dispensed. An inner wall 11 retains the cards within the inner casing and serves to displace the clip 4 when extended for filling.

The foot 6 prevents a complete removal of the inner casing.

The outer casing 1 is provided with notches 12 in the sides at the open ends, affording gripping surface on the inner casing for displacing said inner casing with the fingers. 60

In operation, my invention is as follows:

To fill the case the inner casing 2 is withdrawn to its extreme position as shown in Fig. 3 of the drawings the rear wall serving to displace the spring clip 4 and hold said

clip tightly against the cover thereby allowing cards 3 to be inserted. The foot 6 marks the extreme limit of movement and prevents the removal of the inner casing 2 past the clip 4. The casings are now telescoped 70

whereby clip 4 is released and foot pad 7 is brought in contact with the uppermost card 3. The friction between pad 7 and card 3 being greater than the resistance offered by the inclined wall 9, the card is 75

not carried with the telescoping movement of the casing but slides along the surface of the next lower card where the friction is less than the resistance of wall 9, and is dispensed through the slot 11 in such manner 80

as to be readily grasped by the fingers and removed. Upon the removal of the first card the spring clip brings the friction pad 7 in contact with the next lower card. If 85

now the inner case is partially removed all the cards 3 are carried forward with it by 90

the rear wall 11 of said inner casing, but upon retelescoping the casings now the uppermost card is again held by friction 95

against the pad 7 and is directed upwardly 90 through slot 10 by wall 9. In similar manner the remaining cards are dispensed singly 95

as desired.

The pad 7 forming the friction surface for foot 6 is made of rubber or any fibrous 95 material having a high coefficient of friction and is held firmly against the cards by the spring clip 4. The forwardly inclined teeth 8 shown in Fig. 5 of the drawings gives an increased gripping effect in 100 holding the uppermost card against the displacing force of the inclined wall 9.

The angle at which the forward wall 9 of the inner casing is inclined is designed to afford sufficient resistance to overcome 105 the friction between the cards 3 and prevent their upward displacement, and at the same time allow the upward displacement of the uppermost card as held by the greater friction of the pad 7.

It is at once seen that my invention provides a compact carrying case for calling

or business cards having a novel means for dispensing said cards singly without fumbling with fingers in securing a single card, and the soiling of cards commonly resulting from such fumbling, as commonly occurs with cases of the type now in use. The case may be constructed of cheap cardboard or of any degree of elaborate metal design to suit the requirements of individual users, the principal of construction being the same regardless of the external design.

Having thus fully and clearly described my invention, what I claim as new and desire to secure by Letters Patent is:—

- 15 1. A dispensing card case comprising telescoping casings provided with a slot and inclined inner wall at one end thereof; a spring clip suitably secured within said casings for normally engaging and thereby dispensing cards singly therefrom when the casings are moved relatively to each other.
- 20 2. A dispensing card case comprising telescoping casings provided with a slot and inclined wall at one end thereof; a spring clip suitably secured on the inner surface of the outer casing for normally engaging and thereby dispensing cards singly through

said slot when the casings are moved relatively to each other.

3. A dispensing card case comprising telescoping casings provided with a slot and inclined inner wall at one end thereof; a spring clip provided with a friction producing foot and pad secured on the inner surface of the outer casing for normally engaging and thereby dispensing cards singly through said slot when the casings are moved relatively to each other.

4. A dispensing card case comprising telescoping casings provided with a slot and inclined wall at one end thereof; a spring clip provided with a friction producing foot and pad suitably secured on the inner surface of the outer casing for normally engaging and thereby dispensing cards singly through said slot when the casings are moved relatively to each other; a wall forming a part of the inner casing for displacing the clip and retaining said inner casing partially within the outer casing when filling with cards.

In witness whereof I hereunto set my signature.

DAVID W. STEVENSON.
